UNITED STATES PATENT OFFICE.

LOUIS MAY, OF SAN FRANCISCO, CALIFORNIA.

PENCIL-HOLDER.

957,787.

Specification of Letters Patent. Patented May 10, 1910.

Application filed January 3, 1908. Serial No. 409,228.

To all whom it may concern:

Be it known that I, LOUIS MAY, a citizen of the United States, residing in the city and county of San Francisco and State of 5 California, have invented new and useful Improvements in Pencil-Holders, of which the following is a specification.

My invention relates to pencil holders and particularly to one wherein gripping jaws 10 are adapted to be engaged with the stub portion of a pencil, means being employed for movement on the jaws to move them into gripping action with the stub of the pencil to hold it accurately positioned.

15 In the drawing, forming a portion of this specification and in which like numerals of reference indicate similar parts in the several views:—Figure 1 is a side elevation of my improved pencil holder, the clamping 20 jaws being shown in their expanded positions. Fig. 2 is a sectional elevation of the pencil holder showing the clamping sleeve engaged with the gripping jaws to move them toward each other.

25 My improved pencil holder consists of a hollow inner tubular member 1 and a sleeve 2, the latter being mounted on the former to slide thereon longitudinally. The member 1 at its outer end is split longitudinally 30 to provide a pair of spring gripping jaws 3, each being formed intermediate of its length with a bulge 4. These bulged portions of the jaws are so constructed that they are provided with stop shoulders 5 for a purpose 35 to be hereinafter described.

The sleeve 2 is formed with an enlarged portion 6 and with a contracted portion 7 which are so connected with each other as to form a stop shoulder 8 which is adapted 40 to be engaged by the stop shoulders 5 on the bulged portions 4 of the gripping jaws to limit the sliding movement of the sleeve in one direction. It will be seen that the walls of the enlarged portion 6 of the sleeve 45 are spaced from the walls of the tubular member and that the walls of the contracted portion 7 are engaged with the walls of the tubular member. This construction is such that the sleeve can be moved on the tubular 50 member with very little friction between it and the said tubular member. To limit the sliding movement of the sleeve in an opposite direction the member 1 is formed at its inner end with a collar 9 which is adapted 55 to be engaged by the sleeve as shown in

Fig. 1 of the drawing. The sleeve 6 is provided with a hook 10 which, when the holder is inserted in the pocket, is adapted for clamping engagement with the outer wall of the pocket to hold the holder against loss. 60 The interior walls of the portion 6 of the sleeve are adapted for frictional engagement with the bulged portions 4 of the gripping jaws as shown in Fig. 2 of the drawing so that the said gripping jaws can be 65 moved toward each other to lie approximately in parallel relation. When the sleeve 2 of the holder is moved to assume the position shown in Fig. 1 the gripping jaws will tend to separate from each other 70 and the worn pencil or stub may be discharged and a new stub substituted therefor and the sleeve 2 again moved into gripping engagement with the jaws.

I claim:—

75 A pencil holder comprising a hollow tubular member, said member being split longitudinally to provide gripping jaws adapted for clamping engagement with the pencil, each jaw being formed intermediate 80 of its length with a bulged portion which is formed at its inner end to provide a shoulder, a sleeve mounted to slide on the tubular member and provided with an enlarged portion whose walls are spaced from 85 the walls of the said tubular member and provided with a contracted portion whose walls are engaged with the walls of the tubular member, said enlarged and reduced portions of the sleeve being connected to 90 together by a shoulder which is adapted to be engaged by the shoulders of the bulged portions of the jaws to limit the sliding movement of the sleeve in one direction, the said tubular member having a collar formed 95 thereon at its opposite end to engage the sleeve to limit the sliding movement thereof in an opposite direction, the enlarged portion of the said sleeve being constructed whereby its inner walls may be engaged with 100 the outer surfaces of the bulged portions of the gripping jaws to move the jaws toward each other and into clamping engagement with the pencil.

In testimony whereof I affix my signature 105 in presence of two witnesses.

LOUIS MAY.
